METHOD AND MEANS FOR MEASURING
POWER OUTPUT OF HIGH-FREQUENCY
SIGNAL GENERATORSWilliam A. Stewart, Philadelphia, Pa., assignor,
by mesne assignments, to Philco Corporation, a
corporation of Pennsylvania

Application October 13, 1944, Serial No. 558,493

12 Claims. (Cl. 171—34)

1

This invention relates to an electrical apparatus and more particularly to a system and method of measuring power and power output of an unknown signal generator. In many instances, it is essential to measure the amount of power at a pre-determined frequency in a circuit or being supplied by a generator. It is difficult to supply energy at a fixed critical frequency in high frequency operation due to vagaries of the system and instability of the oscillator. This is particularly true if the system includes sharply resonant high "Q" circuits and operates at low energy levels. Rather than attempt to supply energy at one desired frequency, this invention provides means whereby the frequency is varied over a pre-determined range which range includes the desired or critical frequency at which power is to be measured. Inasmuch as power is a function of energy and time, it is clear that the rate of sweep over the frequency range will be an important factor.

Furthermore, an oscillator having a variable frequency may have the frequency deviation and deviation rate controlled to distribute its energy over a predetermined frequency spectrum. Thus, any desired fraction of oscillator power output may be disposed in any desired part of the frequency spectrum. After calibration with respect to some particular deviation range and deviation rate, the determination of unknown oscillator output powers is a mere matter of arithmetically proportioning the deviation rate and range.

In addition to power measurement, it is frequently desirable to calibrate the power output of a frequency generator. The invention herein-after described permits this to be done in a simple and effective manner.

The invention in general provides an oscillator whose frequency may be varied over a pre-determined range at a pre-determined rate. The output may be fed either in its original form or in the form of a derived frequency to a sharply critical resonant circuit and the selected frequency may then be applied to suitable power measuring means. The oscillator whose power is to be calibrated may then be substituted for the first-named oscillator, and either this substituted oscillator or the remainder of the system is so adjusted that the original or derived frequency of the substituted oscillator will pass through the resonant circuit. The calibration may be carried out in a simple manner in terms of the known characteristics of the sharply resonant circuit, the range of frequency variation or deviation and the rate of frequency variation or

2

deviation rate. It is also possible to measure the insertion loss of a passive network by taking measurements with the passive network included in the energy path between the oscillator and sharply resonant circuit. The insertion loss may then be calibrated in terms of frequency deviation and deviation rate.

For a further description of the invention, reference will be made to the drawings wherein Figure 1 is a circuit diagram embodying the invention and Figure 2 shows some curves illustrating the operation of the system.

An oscillator generally designated as 10 is adapted to have its frequency varied by means generally indicated as 11. As illustrated in the drawing, oscillator 10 is of the electron coupled type and the frequency thereof may be varied by a reactance tube system. Oscillator 10 as illustrated here comprises multi-electrode vacuum tube 12 having control grid 13 connected through blocking condenser 14 to tank circuit 15. Tank circuit 15 comprises inductance 16 and variable condenser 17 connected across the inductance. Tank circuit 15 has lower terminal 18 grounded. From intermediate point 19 of inductance 16 line 20 goes to cathode 21 of vacuum tube 12. Cathode 21 may be energized by suitable heater 23 fed by any source of current. Both terminals of the heater supply are preferably by-passed by grounded condensers 24 and 25. Accelerating electrode 26 in tube 12 is maintained at a suitable positive potential by connection through line 27 to junction point 28 between a series of resistances 29 and 30 and connected between B plus and ground. Vacuum tube 12 has anode 32 energized through radio frequency choke 33 from B plus. Bypass condensers 34 and 35 are provided for grounding B plus and accelerating electrode 26 respectively for radio frequency. In order to vary the resonant frequency of tank circuit 15, means are provided for introducing a controllable phase angle between voltage and current. This means generally indicated by rectangle 11 is coupled to tank circuit 16 through line 37, the return circuit being through ground. Line 37 has resistance 38 connected between it and junction point 39. From junction point 39, small condenser 40 is connected to ground. Resistance 38 is large compared to the reactance of condenser 40 for the radio frequency in tank circuit 15. Thus the radio frequency current through resistance 38 and condenser 40 will be substantially in phase with the radio frequency voltage across tank circuit 15. The voltage across

condenser 40 will be substantially 90 degrees behind the current.

Line 37 is also connected through coupling condenser 41 to anode 42 of reactance tube 43. Reactance tube 43 is preferably of the multi-grid type and as shown here has cathode 45 connected to ground through suitable bias resistance 46 bypassed by condenser 47. Control grid 48 is connected back to junction point 39 and also is connected to ground through grid resistor 49. Screen grids 50 and 51, these being grids number 2 and 4 respectively, are connected together to junction point 52, which point is bypassed by grounded condenser 53 and these grids are maintained at a suitable positive potential through dropping resistor 55 connected to junction point 56 which is supplied with suitable B plus potential. Junction point 56 is connected to anode 42 of the vacuum tube through radio frequency choke 57. Suppressor grid 58, this being grid number 5, is connected in the usual fashion to cathode 45.

Modulating grid 60, this being grid number 3, in the tube is maintained at suitable direct potential by means not shown and is modulated in a desired manner by audio frequency oscillator generally designated as 61. Audio frequency oscillator 61 may have manual frequency control 62 for varying the frequency. Thus if the output is sinusoidal, oscillator 61 may be of so-called Wien bridge type, an example of which is shown on page 505 of Radio Engineer's Handbook (1943 edition) by Terman.

The audio frequency output from 61 thus results in a variation of phase angle in line 37 at an audio frequency rate. This effectively varies the resonant frequency of tank circuit 15 which resonant frequency is preferably in the radio frequency range and may even be in the ultra-high frequency range.

For calibrating purposes, it may be desirable to provide means for indicating a particular frequency within the range of frequencies existing within tank circuit 15. This may be done by loosely coupling to inductance 16 pick-up coil 65 feeding wave meter 66. Wave meter 66 is preferably of the type capable of substantial accuracy and may include a suitably calibrated crystal as part of the meter system. An example of a frequency meter which may be used is given on page 395 of 1944 edition of the Radio Amateur's Handbook. Other types of wave meters may be used.

The modulated radio frequency of vacuum tube 12 is fed from anode 32 by line 68 through coupling condenser 69 and switch 70 to converter or mixer 71. This may be any one of a number of well known circuits. Thus a pentagrid converter as shown on page 570 of Terman's book may be used. Mixer 71 is adapted to combine the output of oscillator tube 12 with fixed frequency local oscillator 72. Oscillator 72 is of any suitable type such as shown in dotted rectangle 10 with the exception that the frequency is fixed at a predetermined value. Oscillator 72 may have its frequency either above or below the range fed from tube 12 in a manner well known in the superheterodyne art. The output of mixer 71 may be fed to control grid 74 of cathode follower 15. Grid 74 is provided with the usual grid resistance 76 to ground while cathode 77 of the vacuum tube is grounded through suitable load resistance 78. Vacuum tube 75 has anode 79 connected to a suitable source of B plus potential.

The output of cathode follower 15 is taken across load resistance 78 to line 80 and supplied

to filter circuit 81 having extremely sharp selectivity. Such a circuit is shown in the form of a series resonant circuit consisting of inductance 82 and condenser 83. This, however, is merely exemplary. Thus sharply resonant filter circuit 81 may consist of a crystal system or a multi-section filter, or if the frequency is high enough, of a cavity resonator. Short sections of transmission line for high frequencies may also be used. In the event that cavity resonators and transmission lines are used, ultra-high frequency oscillators may be necessary. In any event, filter circuit 81 has a high Q and has an extremely sharp resonant characteristic. The output of filter 81 is fed to line 84 and thence to grid 85 of cathode follower tube 86. Grid 85 is provided with usual grounded grid resistance 87. Tube 86 has anode 88 connected to a suitable source of B plus potential while cathode 89 is connected to ground through load resistance 90. The output of cathode follower 86 is fed through switch 91. In one position of switch 91, terminal 92 is connected to anode 93 of diode 94. Diode 94 has cathode 95 connected through condenser 96 and limiting resistance 97 to ground. Volt meter 98 is connected across condenser 96 to ground to indicate the potential existing across the condenser terminals. It is understood that the various cathodes are suitably energized by heaters. Switch 91 in its other position is adapted to feed terminal 100 and thence grounded volt meter 101.

Referring back to the mixer input, switch 70 is adapted to cut-off oscillator 12 and supply the mixer with output from calibrated signal generator 102. Signal generator 102 may be any one of a number of radio frequency oscillators having desired stability and adapted to be manually adjusted for generating any one of a number of frequencies.

During operation, oscillator 10 will generate an output whose frequency will vary over a pre-determined range at a pre-determined rate. It is understood that the actual frequency output of oscillator 10 may be varied in a manner different from that shown and for example may be varied by mere manual control of tuning condenser 11. Thus a simple motor drive may be provided for oscillating this condenser at a pre-determined rate, the rate being adjustable by some manual control over motor speed. This variable output will beat against the fixed output of oscillator 12 to provide a beat frequency of variable value. This variable beat frequency is fed through isolating cathode follower 15 and then applied to high Q filter system 81.

Referring to Figure 2, the dotted line curve shows the variable frequency output due to oscillator 10. The actual value of the frequency may either be the output of oscillator 10 or the beat frequency output from mixer 71. In any event, it is clear that the band covers a substantial range of frequencies. Within this range is a narrow band of frequency indicated by the full resonance curve. This narrow band indicates the frequencies at which filter circuit 81 is responsive. Thus as the variable frequency oscillates between the two extreme values, it passes through the resonant frequency of filter circuit 81.

It is important that the speed with which the frequency output from oscillator 10 is varied should be low enough so that circuit 81 has sufficient time within which oscillations may build up to full value. The higher the Q of circuit 81, the greater the number of cycles will be required within which to build up maximum amplitude

therein. In practice, the modulating frequency for oscillator 10 may be anything within the audio frequency range since at radio or ultra-high frequencies, only a few microseconds are required for the build-up process.

The filtered output from 81 is applied through isolating cathode follower 86 to an integrating device and thence to a power measuring means. As shown here, the integrating device consists of a diode, condenser and resistance. The voltage across condenser 96 and resistance 97 may be indicated by volt meter 98. It is evident that the voltage indicated by meter 98 will be proportional to the peak voltage fed to the condenser and the sweep frequency from one end of the high frequency range to the other.

It is quite important that impedance matching be present between the mixer and the various components feeding into the mixer. Thus maximum energy will be delivered to cathode follower 75 under all operating conditions.

In order to calibrate the entire system, it is necessary to determine the frequency range over which oscillator 10 operates. This is done by means of wave meter 66. The relative output of oscillator 10 may be plotted for various frequencies to obtain a curve such as shown in dotted outlines in Figure 2. It is also necessary to know the rate of deviation or modulation of output from oscillator 10. This may be done by measuring the frequency in line 37 from the reactance tube. The resonance curve of filter circuit 81 must also be known and this may easily be determined by adjusting oscillator 10 and reading indications either in meters 101 or 98, whichever one happens to be on.

For calibrating in terms of absolute power, it will be necessary to provide some device which puts out a measured amount of power at a definite frequency. Thus a signal generator 102 which has been previously calibrated may be used as the standard. This signal generator feeds mixer 71, it being understood that switch 70 is operated to cut-off oscillator 10. The frequency of the signal generator is such that the beat frequency supplied to filter 81 is the resonant frequency of this filter. The energy then goes on through cathode follower 86 and is switched to meter 101 which may be of the hot wire type. The meter indication is noted. After noting the meter reading due to signal generator 102, oscillator 10 is adjusted manually to the same frequency as signal generator 102 and the output is fed to mixer 71. It is understood that signal generator 102 is cut off.

Through wave meter 66, the equality of frequency output of oscillator 10 and signal generator 102 is assured. The output is fed as before and the indication in meter 101 is again noted. The ratios of power from generator 102 and oscillator 10 will be in direct proportion to the meter readings. This calibrates the power output from oscillator 10 at a pre-determined frequency as far as meter 101 is concerned.

In the event that oscillator 10 puts out more power than the calibrated signal generator and if it is desired to obtain the same meter reading, then the following procedure may be provided. Oscillator 10 may have its frequency varied at a known rate and over a known frequency range. The deviation or deviation rate or both may be adjusted so that the reading in meter 101 is the same as that due to calibrated signal generator 102. Then a simple arithmetical proportion involving the deviation and deviation rate will give

the proportion of power transmitted through the sharply resonant circuit to the total power put out by oscillator 10. The total power put out by oscillator 10 may then be computed in terms of the power of calibrated generator 102.

In order to calibrate for meter 98, it is desirable to modulate oscillator 10 at a known rate and deviation and observe meter reading 101. Since the modulation rate and deviation is known, the integrated power in meter 101 is readily determinable. Furthermore by modulating oscillator 10 at a very low frequency such as 10 cycles per second, the reading of hot wire meter 101 will give the true amount of power put out by oscillator 10 at a particular frequency. Switch 91 may now be operated to cut out meter 101 and connect the integrating meter system coupled to terminal 92. The indication on meter 98 may now be compared to the indication on meter 101 for the slow modulating frequency and the scale marked accordingly. Thereafter the modulating frequency for oscillator 10 may be stepped up to any desired value consistent with proper operation of filter circuit 81. Meter 98 indicates a voltage which is either the peak voltage impressed on the integrating system or a definite fraction of the peak, depending upon the type of instrument. The voltage indicated by meter 98 will also be proportional to the deviation rate, the higher the deviation rate, the greater the voltage reading. It is, therefore, understood that, in calibrating meter 98, it will be necessary to take as a factor the normal deviation frequency as compared to the assumed deviation frequency of ten cycles per second.

It is only necessary to calibrate for one frequency and thereafter power output at other frequencies may be easily determined. Thus filter circuit 81 may be varied or oscillator 72 may be varied so that the frequency passed through filter 81 may be moved over a range of frequencies. In the event that filter circuit 81 is varied, it will be necessary to calibrate the resonance curve for this circuit.

It is also possible to calibrate power readings in the following manner. Thus assume that a steady frequency at a known power level is applied. This should result in a resonant beat frequency for filter 81. Reading on meter 101 is noted. Then modulation of the frequency is effected at a known rate and deviation and the proportion of power at the one frequency handled by filter 81 may be calculated. The reading of meter 98 should then show that power proportion.

Once the entire system has been calibrated, it is possible to measure attenuation characteristic of networks. Thus there may be inserted at any suitable place in the system such as for example between oscillator 10 and mixer 71 an attenuating pad or network 105. By noting the power or voltage in meter 98 before and after inserting attenuating network 105, it is possible to calibrate the attenuation constant of network 105. This may be expressed in decibels, nepers, or any other standard desired.

By virtue of the modulation of the high frequency output from oscillator 10 along a frequency range, as shown in Figure 2, it is possible to use extremely delicate and sensitive instruments for measurement. Thus as an example, let it be assumed that oscillator 10 has a frequency range of between one and two megacycles per second. Also let it be assumed that this variation occurs at the rate of 100 cycles per second.

This means that an intermediate frequency will be reached twice per cycle or once per 5000 microseconds. Thus the rate of frequency variation will be 200 cycles per microsecond. For resonant circuits, the band width between half power points on the resonance curve divided by resonant frequency is either one or two over the circuit Q, depending upon the type of circuit. Let it be assumed as two over Q. Then if Q is 10,000 as one example, and the resonant frequency is 1.5 megacycles, the band width comes out as 300 cycles. Since the frequency variation is 200 cycles per microsecond, it is clear that filter circuit 81 will be effectively energized for 1.5 microseconds. During this time, there will be about 1,000 cycles so that oscillations in filter circuit 81 will build up to maximum value with little difficulty. Actually, the Q of circuit 81 could be much higher.

By using a heterodyne principle, it is possible to have oscillator 10 go up to any high frequency desired. The intermediate frequency may be kept at a desirable value so that proper operation is assured.

It is possible to calibrate the output of various generators by inserting them in place of 102 and reading the calibrated meters. Since power is independent of frequency, calibration over great ranges is possible.

What is claimed is:

1. A method of calibrating an oscillator which comprises feeding a known amount of power at a definite frequency, passing said frequency through a circuit sharply resonant thereto, obtaining a meter indication at the output of said resonant circuit as a standard reading, supplying an unknown amount of power at a variable frequency to said resonant circuit with the variable frequency including as a part thereof the frequency to which said circuit is resonant, determining the portion of unit time during which said unknown power is delivered at the frequency to which said circuit is resonant, measuring the power passed by said sharply critical circuit, and including the proportionality factor to determine the true power generated by the unknown source.

2. A method of calibration which comprises feeding power at a fixed frequency to a circuit sharply resonant thereto and impressing said power on a meter, feeding power at a variable frequency to said sharply resonant circuit, said variable frequency including said fixed frequency, impressing said power on a meter, and calibrating one reading in terms of the other reading.

3. In a test system of the character described, an oscillator, means for cyclically varying said oscillator over a frequency range at a definite rate, manually adjustable means for varying the frequency range and rate, means including a sharply resonant circuit for receiving said oscillator output to obtain periodic pulses of energy transmitted through said resonant circuit, said resonant circuit having known resonance characteristics and forming part of the permanent test system, said frequency variation and Q of said resonant circuit being so related that oscillations may attain a maximum value at each pulse in said resonant circuit, and means calibrated to indicate power, said means being responsive to the energy level in said pulses, said indicating means giving an indication directly proportional to the power at the output of said resonant circuit whereby said system may be used to calibrate the power output of an unknown oscillator when substituted for said first-named oscillator.

4. In a test system of the character described,

an oscillator, means for cyclically varying said oscillator over a frequency range at a definite rate, manually adjustable means for varying said frequency range and rate, means including a sharply resonant circuit for receiving said oscillator output to obtain periodic pulses of energy transmitted through said resonant circuit, said resonant circuit having known resonance characteristics and forming part of the permanent test system, said frequency variation and rate of variation and Q of said resonant circuit being so related that oscillations in said resonant circuit will build up to maximum value at each pulse, means for integrating said pulses, and indicating means responsive to the energy level in said integrating means, said indicating means being calibrated to show the power passed by said resonant circuit whereby said manually adjustable means may be operated to give an indication equal to the indication given by an unknown oscillator substituted for said first-named oscillator.

5. The system of claim 4 wherein said integrating means includes a condenser and resistance and wherein said indicating means is a volt meter connected across said condenser and resistance.

6. In a test system of the character described, the combination of an oscillator adapted to operate over a range of frequencies in a radio frequency band, means for cyclically varying said oscillator frequency output over said range, manually adjustable means for varying said range of frequency and the rate at which said frequency varies, means for beating said variable frequency with a fixed frequency to generate a difference frequency varying over a different predetermined range, a filter circuit fed by said difference frequency and responsive to a frequency within the range of variation of said difference frequencies, said filter circuit having known filter characteristics and forming part of the permanent test system, and indicating means responsive to the energy level in said pulses at the output of said filter, said indicating means being calibrated to show the power at the output of said filter.

45 7. In a test system of the character described, the combination of an oscillator adapted to supply power at low level, means including a circuit having a sharp frequency response characteristic fed by said oscillator, said resonant circuit having known resonance characteristics and forming part of the permanent test system, manually adjustable means operating on said oscillator for supplying energy to said sharply resonant circuit in the form of pulses at a desired pulse repetition rate, said manually adjustable means being adapted to vary said pulse repetition rate, and means fed by said sharply resonant circuit for integrating the pulses of energy and indicating the power in said pulses, whereby an unknown oscillator substituted for said first-named oscillator may have its output calibrated.

8. The system of claim 7 wherein a fixed oscillator is provided for beating said first oscillator output to provide a difference frequency and wherein said difference frequency is fed to said sharply resonant circuit.

9. In a test system of the character described, the combination of an oscillator adapted to operate at least at radio frequency, manually adjustable means for cyclically varying said oscillator frequency over a range at a definite rate, means including a high Q sharply resonant circuit for receiving said oscillator output, said high Q circuit having known resonance characteristics and forming part of the permanent test system

and being adapted to pass a narrow frequency band so that, when said oscillator is frequency modulated, energy in the form of pulses is passed through said high Q circuit at a definite rate, said rate being sufficiently slow so that the potential may build up to a maximum value in said high Q circuit during each pulse, a vacuum tube amplifier stage fed by said high Q circuit, said stage having an output circuit, a rectifier, condenser and resistance in series in said output circuit, 10 said output circuit being adapted to function as an integrator of said energy pulses, and means for indicating the potential across the condenser and resistance, said potential indicating means being calibrated to indicate power with reference to the energy output of said oscillator, said oscillator being adapted to be replaced by an oscillator of unknown power whereby the relative power output of said unknown oscillator may be compared to said first-named oscillator.

10. The system of claim 9 wherein a watt meter is provided and wherein switching means are provided for cutting out said integrating means and inserting said watt meter whereby said potential indicating means in said integrating means may be calibrated with reference to said watt meter.

11. A method of determining the insertion loss of a passive network which comprises feeding power at a variable frequency to a sharply resonant circuit, varying said frequency at a slow 30

enough rate so that the resonant frequency may build up to a maximum, integrating the pulses of energy passed by said sharply resonant circuit, measuring the energy level of said integrated pulses, then inserting said passive network so that the variable frequency is impressed on said network and thence on said sharply resonant circuit and adjusting the frequency variation so that the energy level is the same whereby the insertion loss may be computed.

12. A method of calibration which comprises feeding alternating current power to a circuit sharply resonant thereto and impressing the power output of said resonant circuit on a meter, feeding alternating current power in the form of pulses to said resonant circuit and impressing said pulse power output of said resonant circuit on a meter system, and calibrating one reading in terms of the other reading.
